UNITED STATES PATENT OFFICE.

CHRISTOPHER JAMES WALBRAN, OF BROOKLYN, NEW YORK, ASSIGNOR TO KLEIN-SCHMIDT ELECTRIC COMPANY, INC., OF LONG ISLAND CITY, NEW YORK, A CORPORATION OF NEW YORK.

TAPE-PASTING DEVICE.

Application filed June 28, 1922. Serial No. 571,379.

To all whom it may concern:

Be it known that CHRISTOPHER JAMES WALBRAN, a citizen of the United States, and resident of Brooklyn, in the county of 5 Kings and State of New York, has invented certain Improvements in Tape-Pasting Devices, of which the following is a specification.

Modern printing telegraphy records its 10 received messages by means of tape printing or page printing. In using the former method, it becomes necessary to paste the tape, upon which the message has been printed, on a suitable support, such as a receiving blank, so as to make it handier to 15 read and easier to handle and file. The present invention has for one of its purposes the provision of a pasting device of great simplicity and efficiency, to expedite the 20 pasting of such a tape upon a support.

The device is shown in Fig. 1, in a vertical, longitudinal section, Fig. 2 is a top view of the device and Fig. 3, a vertical transversal section, on line 3—3 of Fig. 1.

25 A casing 10, of suitable material, having a substantially circular cross section, is provided, on its upper side, with a guiding device or channel 11, for receiving tape 12, upon which the telegraphic message has been 30 printed.

One end of casing 10 is tapered and provided with a recess or flat groove 13, preferably aligned with tape channel 11, so that tape 12, when leaving channel 11 may pass 35 groove 13 to and underneath pressure roller 14, to the message blank or other surface, upon which it is intended to be pasted. The upper side of tape 12 receives the printed message, for instance, "The quick brown 40 fox etc." and the lower side is, preferably, provided with an adhesive material, dried thereon, to be moistened, as hereinafter set forth, though no dried preparation may be placed upon this side of tape 12, but a liquid 45 adhesive may be applied to it by the device itself.

Tape 12 can be held stationary, or its 50 tension and movement controlled, by means of roller 15, pivoted in bearings 16 of spring 17, the resiliency of which can be adjusted by means of set screw 18, which also regulates the pressure of roller 15 upon tape 12.

Within casing 10, there is provided a

55 container 19, which may hold water, to provide moisture for the adhesive side of tape 12, or may contain a liquid adhesive, such as mucilage, to be applied to the tape, before being pasted to a support.

Such moisture, or liquid adhesive, saturates 60 an applicator 20, made of felt or other absorbent material, and inserted in container 19, through a proper tubing of a stopper or other closing means, while its free end is in contact with the lower side of tape 12 and 65 applies moisture or liquid thereto. The end of casing 10, opposite to that used in applying tape to a support, is closed with a suitable cap 21, resiliently holding the moisture 70 container 19 and the applicator 20 toward 75 the tapered end of the casing. It will be understood that any well known means for securing cap 21 to body 10 may be employed, as for example, a screw thread connection, or a slot and bayonet joint. 75

In using the pasting device, tape 12 having the printed message on its upper side, is inserted into channel 11, passed under roller 15, through groove 13, over moisture applicator 20 and under roller 14 to the support upon which it is to be secured. The lower side of the tape, being now moist or adhesive, is applied to the support and held thereon and, thereafter, the pasting device is moved toward the right, as viewed in Fig. 80 1, exerting pressure upon roller 14 and tape 12 held thereunder, whereby a length of tape is secured to the support, approximately 85 equal to the width of the support. By watching the printed matter in the space 90 between the rollers 15 and 14, it is easy to tear the tape at a suitable place, preferably between two words, by a simple twist of the hand holding the pasting device and pressing a finger of the other hand close in front 95 of roller 14, upon tape 12, whereupon a new line of tape may be started from the left side of the support, until the entire message is pasted thereon. 100

Claims.

1. In combination, a casing having an inclined end, a channel on said casing for receiving and guiding material to be moistened, a spring-pressed roller at one end of 105 said channel and at the top of the incline of said casing, a pressure roller at the base of the incline of said casing, a container for liquid in said casing, an absorbent member

- extending into said container and adapted to apply liquid from said container to the lower side of the material to be moistened, and a closing cap at the other end of said 5 casing, having a spring to apply pressure to the adjacent end of said container.
2. A device for moistening material, comprising a casing, a guide for the material to be moistened on said casing, a liquid container in said casing, and means extending through said casing into said guide for moistening one side only of the material with liquid from said container.
3. The combination as set forth in claim 15 2 in which said means comprises a strip of absorbent material.
4. The combination as set forth in claim 2 together with resilient means for holding said moistening means in engagement with 20 the material to be moistened.
5. The combination as set forth in claim 2 in which said means comprises a strip of absorbent material, together with a spring for pressing said container against the forward end of said casing to maintain said absorbent material in engagement with the 25 material to be moistened.
6. The combination as set forth in claim
- 2 together with a roller spring pressed into said guide to control the tension of material to be moistened in passing over said moistening means. 30
7. The combination as set forth in claim 2 together with a roller spring pressed into said guide to control the tension of material to be moistened in passing over said moistening means, and means for manually varying the pressure exerted by said roller on the material to be moistened. 35
8. The combination as set forth in claim 2 in which the forward end of said casing at the end of said guide is shaped to form a knife edge with which the moistened material may be torn.
9. The combination as set forth in claim 2 in which the forward end of said casing at the end of said guide is shaped to form a knife edge with which the moistened material may be torn, together with a pressure roller supported at the end of said guide 40 and over said knife edge. 50

Signed at New York, in the county of New York and State of New York, this 24th day of June, 1922.

CHRISTOPHER JAMES WALBRAN.
